WELL CONTROL HEAD

Edmund J. Roach and Edward F. Cooke, Jr.,
Beaumont, Tex.

Application December 16, 1941, Serial No. 423,212

4 Claims. (Cl. 166—14)

This invention relates to casing control heads in which the slip bowl unit which suspends the inner casing from the casing head is characterized by having captive slips, that is to say, having slips which are irremovable from the slip bowl whenever the inner casing is in place within the slip bowl.

One of the objects of the invention is to provide a slip bowl with a downwardly tapered slip seat in which the bowl is provided with an inwardly extending flange restricting its bore at the upper end, and the slips are temporarily retained in the upper flared portion of the bore, spread apart to permit the free passage of the inner casing, by being bolted to said flange.

Other objects of the invention will appear as the following description of a preferred and practical embodiment thereof proceeds.

In the drawings throughout the several figures of which the same characters of reference have been employed to designate identical parts:

Figure 1 is an axial section through a well control head embodying the principles of the subject invention;

Figure 2 is a cross-section taken along the line 2—2 of Figure 1;

Figure 3 is a cross-section taken along the line 3—3 of Figure 1;

Figure 4 is a longitudinal axial section through a modified form of the invention;

Figure 5 is a cross-section taken along the line 5—5 of Figure 4;

Figure 6 is a cross-section taken along the line 6—6 of Figure 4;

Figure 7 is a longitudinal axial section through a further modified form of the invention;

Figure 8 is a cross-section taken along the line 8—8 of Figure 7.

Referring now in detail to the several figures, and first advertizing to that form of the invention disclosed in Figure 1, the numeral 1 is a casing head having a lower threaded portion 2 adapted to be screwed to the top of an outer casing 3, having the usual flow line bores 4 above the threaded portion 2, and having a tapered seat 5 above the zone of the flow line bores 4 for the reception of the slip bowl unit, which in general is designated by the reference character 6.

Above the tapered seat 5, the bore of the casing head is cylindrical, and the upper portion of the slip bowl unit 6 has the same external shape.

Packing rings 7 seated in grooves 8 in the seating surface of the slip bowl unit effectively seal the joint between the slip bowl unit and the casing head.

5 The slip bowl unit includes a slip bowl 9 having a longitudinal bore therethrough, the upper part of which is restricted by the inwardly extending flange 10 to an opening 11 just large enough to freely pass the inner casing 12. At an intermediate portion the slip bowl 9 is similarly restricted by an inwardly projecting flange 13.

10 Between these flanges the bore of the slip bowl is expanded into a slip chamber having a downwardly tapered wall 14. A plurality of slips 15 are arranged circumferentially within this chamber, the slips having outer tapered seating surfaces 16 cooperating with the tapered wall 14 of the slip bowl unit, and with inner and preferably serrated faces 17 adapted to grip the inner casing 12.

15 The slips are sufficiently shorter than the length of the slip chamber, so that they may lift from their seats on the tapered wall 14 when the casing 12 is elevated relative to the slip bowl unit. When in elevated position, the slips 15 contact with the upper flange 10, the slips being imprisoned within the slip bowl by the flange 10 when the inner casing 12 is in place.

20 The flange 10 is provided with a plurality of apertures 18, one for each slip, and the slips are provided with threaded sockets 19 in their upper ends. Initially, the slips are bolted against the flange 10 by the bolts 20, which pass through the openings 18 and screw into the sockets 19 of the slips. When the slips are thus held upwardly from their seats in the slip bowl they are retracted radially so as to clear the path for the free passage of the inner casing.

25 It is obvious to those skilled in the art that a compressible packing cannot be practically employed on top of the slips as a means to prevent leakage of gas under pressure from the well past the slips. The invention therefore contemplates the use of a metallic welded joint 21 between the top of the casing head and the inner casing. The weld of this joint also seals the openings 18 in the flange 10 after the bolts 20 have been removed.

30 In order to enable a fluid tight welded joint to be made between the top of the casing head and the inner casing 12, it is essential to prevent gas from leaking through the joint to be sealed while the welding operation is in progress. With this object in view, the lower part of the slip bowl 9 below the zone of the lower flange 13 has an enlarged cylindrical bore 22 receiving the compressible packing rings 23 which are normally of a somewhat smaller internal diameter than the external diameter of the casing 12 so as to be com-

pressed into sealing contact with the slip bowl and inner casing 12 by the inner casing. A ring nut 24 screws into the lower end of the slip bowl against the packing, providing additional pressure. The seal between the lower end of the slip bowl and the inner casing also has a value as will appear, in permitting the sealed joint to be tested at any time by the introduction of fluid under pressure into the slip bowl.

The operation of the slip bowl unit is as follows: The slip bowl unit with the slips firmly bolted in an upward position against the inner face of the flange 10 is slipped over the end of the inner casing outside of the accessory blow-out preventers which at the time are secured to the casing head. The ring nut 24 is adjusted to apply the proper sealing pressure to the packing 23. The inner casing, together with the slip bowl unit thus secured to the inner casing solely by the frictional contact of the packing 23 with said casing, is lowered through the blow-out preventers until the slip bowl unit rests upon its seat in the casing head. The inner casing is then pushed downward through the blow-out preventer until it rests either upon the bottom of the well or down to a predetermined point. The accessory blow-out preventers are then removed. The bolts 20 are then unscrewed, letting the slips drop to their seating position upon the tapered wall 14 of the slip bowl. The slips in this position wedgely grip the inner casing. The inner casing may then be lifted through the slip bowl to any desired position and then released, when it will be at once gripped by the slips in its new position. When the inner casing is properly set the joint between the top of the casing head and the inner casing is sealed by the metallic weld 21 which, as has been stated, seals also the empty bolt openings 18.

The particular value of this form of slip bowl unit is that initially the slips are already in position in the slip bowl unit and cannot become lost or displaced. They are also in position to admit the passage of the inner casing without any manipulation of the slips. After having once been installed, it is impossible that the slips may be displaced or removed without breaking the welded seal 21 and removing the inner casing from the slip bowl.

In Figure 4 a slip bowl unit of the captive slip type is shown, in which a threaded bore 25 is provided, opening in the top of the slip bowl and communicating with the slip chamber. The purpose of this bore is to admit fluid under pressure to the slip chamber to test intactness of the welded joint 21. The fluid cannot escape by way of the lower part of the slip bowl, being blocked by the seal formed by the packing 26, which is an alternative form of packing to that shown in Figure 1. This packing has a channel 27 in its top surface, communicating with the slip chamber, and to which channel fluid pressure is admitted. The channel forms a flexible flap 28 engaging the surface of the inner casing 12, the pressure of which against said casing is proportional to the pressure of the testing fluid. Any imperfection in the welded joint 21 is evidenced by the escape of the fluid under pressure by way of said joint. When the joint 21 is not under test, the bore 25 is closed by a threaded plug 37.

Figure 7 shows a combination of casing head 70 and slip bowl unit slightly modified from that form shown in Figure 1, so as to provide means by which the welded joint can be tested at any time during the life of the installation. The casing head is provided with an internally threaded bore 75

29 opening in the surface of the tapered seat 5 in the zone between the packing rings 30 of the slip bowl unit. The slip bowl is provided with inner and outer circumferential channels 31 and 32, respectively, in this same zone, said channels being in communication by way of a passage 33. The inner channel 32 communicates with the longitudinal spaces between the slips. A pipe from the source of fluid under pressure may be connected to the threads 34 of the bore 29 and fluid pressure thus applied to the slip chamber. When the welded joint 21 is not under test, the bore 29 is closed by a suitable plug 35 screwed into the threads 36 of the bore 29.

While we have in the above description disclosed what we believe to be a preferred and practical embodiment of the invention, it will be understood to those skilled in the art that the details of construction and the arrangement of parts as shown and described are by way of example, and not to be construed as limiting the scope of the invention as defined in the appended claims.

What we claim as our invention is:

1. In a casing control head for oil wells, a slip bowl unit comprising a slip bowl having an external seat for sealingly supporting said slip bowl within a casing head, said slip bowl having a bore therethrough for the passage of an inner pipe, the intermediate portion of said bore being expanded to form a slip chamber bounded at the top and bottom by inwardly extending slip retaining flanges, the side wall of said slip chamber being downwardly convergent forming a slip seat, a plurality of slips within said slip chamber circumferentially displaced, means located above the zone of said external seat for releasably suspending said slips from said top flange in which suspended position said slips permit relative up and down movement between the inner pipe and to said slip bowl unit, said slips when released engaging said convergent wall for chocking the inner pipe against downward movement.

2. In a casing control head for oil wells, a slip bowl unit comprising a slip bowl having an external seat for sealingly supporting said slip bowl within a casing head, said slip bowl having a bore therethrough for the passage of an inner pipe, the intermediate portion of said bore being expanded to form a slip chamber bounded at the top and bottom by inwardly extending slip retaining flanges, the side wall of said slip chamber being downwardly convergent forming a slip seat, a plurality of slips within said slip chamber circumferentially displaced, means located above the zone of said external seat for releasably suspending said slips from said top flange comprising a plurality of spaced holes through said top flange and bolts in said holes engaging threaded sockets in the upper ends of said slips, in which suspended position said slips permit up and down movement of the inner pipe relative to said slip bowl unit, said slips when released engaging said convergent wall for chocking the inner pipe against downward movement.

3. In a casing control head for oil wells, a slip bowl unit comprising a slip bowl having an external seat for sealingly supporting said slip bowl within a casing head, said slip bowl having a bore therethrough for the passage of an inner pipe, the intermediate portion of said bore being expanded to form a slip chamber bounded at the top and bottom by inwardly extending slip retaining flanges, the side wall of said slip chamber being downwardly convergent forming a slip

seat, a plurality of slips within said slip chamber circumferentially displaced, means located above the zone of said external seat for releasably suspending said slips from said top flange comprising a plurality of spaced holes through said top flange and bolts in said holes engaging threaded sockets in the upper ends of said slips, in which suspended position said slips permit up and down movement of the inner pipe relative to said slip bowl unit, said slips when released engaging said convergent wall for chocking the inner pipe against downward movement, said bottom flange being provided with an inwardly facing ring groove, and a compressible packing ring seated in said groove adapted to sealingly surround the inner pipe.

4. In a casing control head for oil wells, a slip

bowl unit comprising a slip bowl having an external seat for sealingly supporting said slip bowl within a casing head, said slip bowl having a bore therethrough for the passage of an inner pipe, the intermediate portion of said bore being expanded to form a slip chamber bounded at the top and bottom by inwardly extending slip retaining flanges, the side wall of said slip chamber being downwardly convergent forming a slip seat, a plurality of slips within said slip chamber circumferentially displaced, and means accessible from above the top inwardly extending flange for releasably suspending said slips from said top flange.
